UNITED STATES PATENT OFFICE.

ADELMER M. BATES, OF CHICAGO, ILLINOIS, ASSIGNEE TO BATES VALVE BAG COMPANY, OF CHICAGO, ILLINOIS, A CORPORATION OF WEST VIRGINIA.

CEMENT PACKER.

Application filed June 24, 1922. Serial No. 570,686.

To all whom it may concern:

Be it known that I, ADELMER M. BATES, a citizen of the United States, residing at Chicago, in the county of Cook and State of Illinois, have invented a certain new and useful Improvement in Cement Packers, of which the following is a specification.

This invention relates to a bag filling machine and particularly to the bag supporting, holding and discharge mechanism. It is illustrated more or less diagrammatically in the accompanying drawings, wherein:

Figure 1 is a vertical cross section of a bag filling machine;

Figure 2 is a cross section on line 2—2 of Figure 1;

Figure 3 is a partial plan view of the bottom of the bag holding cradle with parts omitted and parts in section;

Figure 4 is a section on line 4—4 of Figure 3 with parts omitted;

Figure 5 is a vertical cross section taken generally on line 5—5 of Figure 4 showing the locking mechanism and looking from the rear of the bag holding cradle;

Figure 6 is a front elevation of a bag filling machine with parts omitted;

Figure 7 is a detail section on line 7—7 of Figure 1.

Like parts are designated by like characters throughout.

A is the hopper of a bag filling machine into which material to be fed into the bags is introduced. B is a feed wheel adapted to feed a predetermined charge of material into the chest B' which communicates at its bottom with an impeller casing B'', in which is located an impeller B''' by means of which material is forcibly discharged through a feed spout B'' into the bag which has an opening in its top, preferably of the valve type, the discharge nozzle being inserted in the opening and the nozzle itself being controlled by a suitable valve B''.

C is an A-frame guided at its upper end by a check bar C' which is pivoted at C'', in a housing C', to compensate for vertical movement of the A-frame. This housing C' is adjustable in and out by means of the set screw C'' and is held in position by means of the set screw C''. The side members of the A-frame are notched at their bottom as at C''' and rest upon the side members of the scale bar C'', which is not herewith described in detail as it forms no part of the present

invention. Extending downwardly from the side members of the A-frame are a pair of holding members C' which are joined at their bottom, preferably by means of a plate C''.

Mounted within the A-frame and pivoted adjacent its bottom is a bag holding cradle D which is provided with a bag guiding member D' adjacent its upper end against which a bag or package is adapted to rest. In its bottom the cradle D is provided with an adjustable floor plate D'' upon which the bag or package rests. At its upper end the frame is provided with a hook E which is adapted to engage a hook E' mounted on the outside of the chest B'. This hook is provided with a stop member E'' and an adjusting screw E''. Extending laterally from the hopper casing A is a bracket bar F which is provided with a downwardly extending pivoted arm F' which carries adjacent its bottom a controlling handle F''. Adjacent the handle F'' the bar F is connected to the hook E by means of a link F'''.

Supported adjacent the discharge spout B'' are a pair of brackets G between which is pivoted a gripping member G'. This member is notched on its bottom as at G'', and the resultant teeth are arcuate laterally of the spout, as shown in Fig. 6, and, when a bag is moved over the discharge nozzle, the teeth engage the fabric of the same and hold it against displacement. This member is split at its upper end and has pivoted therein a latch G''. Beneath this latch is a lateral extension G''. When it is desired to dump the bag the handle F'' is pulled by the operator and this tips the bag holding cradle. The downward extension G'' adjacent the top of the cradle contacts the latch G'' and by means of it rotates the holding member G' out of contact with the fabric of the bag and so permits the same to be withdrawn from the discharge spout. In reverse movement the latch G'' is free to swing and merely moves out of place to permit the return of the bag holding cradle.

I will now describe the details of the adjustable floor plate and bag holding cradle. The side members of the bag holding cradle adjacent the bottom are notched on their front sides as at H. The bottom plate D'' is provided adjacent its rear with a pair of pins H', H''. These pins are adapted to lie within the notches H in the side members

of the bag holding cradle. On both sides in its rear the floor plate is provided with lugs H^2 which are higher than the pins H' . Beneath the lugs H^2 and a little below the pins H' is a pin H^3 , the lug H^2 and pin H^4 being adapted normally to bear against the rear of the side members of the cradle. The pin H^3 is normally held in the position shown in Figure 5 by means of the helical 10 spring H^4 . When, however, it is desired to adjust the position of the bottom plate this pin is retracted and the front of the bottom plate may then be tipped upwardly and the pins H' moved from the notches H . When 15 in this position, the bottom plate may be moved to any desired height, where the pins H' are again moved into notches, the front of the floor plate rotated downwardly and the pin H^3 allowed to extend again so as to 20 engage the rear of the side members. Thus the parts are held in position again.

The use and operation of my invention are as follows:

A bag or other package is put in position 25 in the cradle and the opening in the top of the bag is moved so that the discharge nozzle extends into it. In this position the fabric of the bag will be engaged by the holding mechanism described. As the 30 bag is filled it gradually depresses the scale beam and when it is completely filled the discharge of material into it is stopped. The hook or stop member E' prevents the outward movement of the cradle until the 35 material in the bag moves the scale beam upon which the cradle is mounted in a manner more fully described in my prior Patent No. 1,209,105, granted December 19, 1916. The handle controlling the cradle is then 40 moved outwardly and upwardly by the operator. The bag is thereby automatically released from the nozzle and is tipped forward and out of the frame. The handle which controls the cradle is, as above de- 45 scribed, supported from above, and its weight is not supported by the scale beam and thus any weight from the hand of the operator upon this controlling handle does not come upon the scale beam so as to upset 50 its balance or otherwise injuriously affect the weighing operation.

Claims:

1. In a bag filling machine, a bag support mounted upon weighing means and adapted to support a bag in filling position, said support including means to remove a filled bag;

a handle supported independently of the weighing means, and a link connecting the handle to the bag removing means.

2. In a bagging machine, a tilttable cradle 60 mounted on a scale beam and adapted to support a bag in filling position, a handle supported independently of the cradle and scale, and a link connecting the handle to the cradle for tilting it.

3. In a bag filling machine, a tilttable cradle supported from and adapted to rise and fall with a scale beam and adapted to support a bag in filling position, means to prevent tilting of the cradle until it is 70 lowered in response to the weight of a filled bag, a handle supported independently of the cradle and scale beam, and a link connecting the handle to the cradle for tilting it.

4. In a bag filling machine, a cradle 75 adapted to support a bag in filling position and tilttable forward to discharge a filled bag, a bottom support for the bag supported by its rear side from the cradle and vertically adjustable when its front side is raised, 80 and a hand operated device normally preventing the raising of the front side of said bottom.

5. In a bag filling machine, a cradle adapted to hold a bag in filling position and 85 tilttable forward to discharge a filled bag, said cradle having vertical side members and a bottom support for the bag supported by its rear side from said side members and vertically adjustable on said members when 90 its front side is raised, and a spring catch normally preventing the raising of the front side of said bottom.

6. In a bagging machine a bag holding 95 frame provided with side members notched along their front edges and smooth along their rear edges, an adjustable bottom member provided with projections adapted to enter said notches and provided with stops above said projections adapted to contact the 100 rear of said side members, said stops being fixed, and a movable stop adapted to contact the rear of one of said side members and when in position to hold the bottom member against rotation and when withdrawn adapted to permit rotation of the bottom member 105 to free the projections from said notches and to permit vertical movement of the bottom member.

Signed at Chicago county of Cook and 110 State of Illinois, this 14th day of June 1922.

ADELMER M. BATES.
